W. G. BRALEY.

BOLT CUTTER.

APPLICATION FILED AUG. 3, 1917. RENEWED OCT. 9, 1918.

1,297,075.

Patented Mar. 11, 1919.

UNITED STATES PATENT OFFICE.

WILBUR G. BRALEY, OF TOWANDA, KANSAS.

BOLT-CUTTER.

1,297,075.

Specification of Letters Patent. Patented Mar. 11, 1919.

Application filed August 3, 1917, Serial No. 184,331. Renewed October 9, 1918. Serial No. 257,531.

To all whom it may concern:

Be it known that I, WILBUR G. BRALEY, a citizen of the United States, residing at Towanda, in the county of Butler and State 5 of Kansas, have invented certain useful Improvements in Bolt-Cutters, of which the following is a specification, reference being had therein to the accompanying drawing.

The present invention has reference generally to improvement in that class of inventions known as metal cutting and punching and more particularly relates to a nut splitter or bolt cutter.

This invention has for its primary object 15 to provide a device of the above character designed for readily splitting nuts so as to easily remove them from bolts when they cannot be removed by the employment of a wrench, and in addition obviating the convenience of using a chisel or hammer 20 with the possibility of injuring the hands.

More particularly, the invention embraces the provision of a device of the above character wherein the construction permits of a 25 quick adjusting of the jaws into a biting or cutting engagement with a nut.

It is the more specific object of this invention to provide a nut-splitter and bolt-cutter wherein common means is provided 30 for guiding the movable jaw, for supporting the object being acted upon and for supporting the adjusting means of the jaws.

Among the other aims and objects of this invention may be recited the provision of 35 a device of the character described with a view to compactness, and in which the number of parts are few, the construction simple, the cost of production low and the efficiency high.

40 Other improvements and novel details in the construction and arrangement of the various parts of the apparatus will be brought out more in detail in the description to follow, which for a clear understanding 45 of the invention should be considered in connection with the accompanying drawings forming a part hereof, and wherein is disclosed for the purpose of illustration a convenient and satisfactory embodiment of the 50 invention. It is to be noted in this connection that minor changes in the construction and arrangement of parts may be made without departing from the principle of operation of the various parts.

The invention is clearly illustrated in the 55 accompanying drawings in which:—

Figure 1 is a side elevation of the machine;

Fig. 2 is a top plan view of the invention;

Fig. 3 is a horizontal section taken on 60 line 3—3, Fig. 1.

Similar characters of reference are employed in all the described views, to indicate corresponding parts.

Referring now more particularly, to the 65 accompanying drawings, there is provided a stationary jaw in the present instance consisting of a straight body 1, formed of suitable metal the inner surface adjacent to the upper end of which is provided with 70 an inwardly extending recess 2, for a purpose which will presently appear. Likewise, the lower end of the body is reduced on opposite sides as indicated by numeral 3.

Cooperating with the stationary body is 75 a movable jaw indicated in this entirety by the numeral 4 and consisting of a prismatic body formed of metal the horizontal portion 5 thereof being bifurcated at its outer end to provide spaced arms 6 which are arranged about the reduced end 3 of the jaw 1, and pivotally connected thereto through the instrumentality of the bolt 7. The inner surface of the vertical portion 8 of the movable jaw is provided with a recess 9 adjacent its outer end at a point substantially 80 opposite the recess 2.

Suitable cutting means are now employed and in the present instance consist of knife dies 10. These dies consist of blade portions 11 from the rear surfaces of which project shanks 12 removably seated in the sockets 2 and 9 so that the cutting edges 85 will be arranged toward each other as indicated in the drawings.

With a view toward providing improved means for guiding the movement of the removable jaw 4 and for serving as a support for the nut 13 to facilitate the cutting and splitting of the same, the yoke indicated in 100 its entirety by the numeral 14 is employed. This yoke is formed from a single piece of strap metal and is bent into U-shaped configuration forming a vertex 15 having a threaded opening 16 therein. Arms 16—17 105 continue from the opposite sides of the vertex and are arranged in close relation with the opposite sides of the jaw 4 and from

opposite sides of the jaw 1 the terminals of the arms 17 of the yoke being pivotally connected to the jaw 1 through the instrumentality of suitable fastening device 18 at a point in proximity to the adjacent knife die 10. In order to adjust the jaws relatively to each other, an adjusting screw 19 is adjustably mounted in the threaded opening 16 and is also adjustable through the threaded bore 20 of the block 21 seated between the arms 17 adjacent the vertex 15. A head 22 is formed in the end of the bolt and is adapted to be engaged by a wrench so that the inner end of the bolt may be adjusted between the arms and against the vertical portion 8 of the movable jaw 4 so as to swing the movable jaw toward the stationary jaw in order that the knife dies 10 will exert a biting and cutting action on the nut 13 positioned therebetween so as to split the nut and allow the ready removal thereof.

It is believed in view of the foregoing description that a further detailed description of the operation of the invention is entirely unnecessary. Likewise it is believed that the advantages of the invention will be readily apparent.

As many changes could be made in the above construction and many apparently widely different embodiments of this invention could be made without departing from the scope thereof, and it is intended that all matter contained in the above description or shown in the accompanying drawings shall be interpreted as illustrative and not in a

limited sense. It is also to be understood that the language used in the following claims is intended to cover all the generic and specific features of the invention herein described and all statements of the scope of the invention which, as a matter of language might be said to fall therebetween.

Having thus fully described my invention, what I claim as new and desire to secure by Letters Patent is:—

In a device as described, in combination, a stationary and a movable jaw, the stationary jaw being a straight bar while the movable jaw is an L-shaped bar, one arm of said movable jaw being pivotally connected to the inner end of the fixed jaw, a guide member having a pair of side arms secured at one end to said fixed jaw short of its outer end, a cross-partition formed between the side arms of said guide member, a screw-shank threaded into said guide member and into said partition, the other arm of said L-shaped jaw projecting between the side arms of said guide member immediately in front of said partition, the free end of the threaded shank adapted to engage said L-shaped jaw in order to force the same toward the fixed jaw, and cutter members each consisting of a stub and a V-shaped blade; each of said jaws at their outer ends being provided with a recess in which the stubs of said cutter members are received.

In testimony whereof I affix my signature.

WILBUR G. BRALEY.
